UNITED STATES PATENT OFFICE.

CHESTER MILLER AGNER, OF SACRAMENTO, CALIFORNIA.

TRANSMITTING MEANS FOR WIRELESS TELEGRAPHY.

1,190,973.

Specification of Letters Patent. Patented July 11, 1916.

Application filed June 8, 1914. Serial No. 843,787.

To all whom it may concern:

Be it known that I, CHESTER M. AGNER, a citizen of the United States, residing at Sacramento, in the county of Sacramento and State of California, have invented a new and useful Transmitting Means for Wireless Telegraphy, of which the following is a specification.

This invention has reference to improvements in transmitting means for wireless telegraphy, and its object is to provide a means whereby certain signals may be sent out from a station in charge of persons unskilled in telegraphy.

Many ships are not required to be provided with wireless outfit, and, therefore, have no means when in distress of communicating with other vessels or stations. For such ships the present invention affords a means whereby the recognized distress call may be sent out, and in addition thereto such information as the location of the vessel and the character of the distress, and the whole apparatus is of a nature requiring no skilled attention or the presence of a trained operator, since it may be put into commission by any person of intelligence without any previous knowledge of wireless telegraphy.

The present invention comprises an equipment consisting of a suitable aerial and a sending set of such capacity as may be deemed necessary, while the signals are caused automatically. This last named feature is accomplished by the provision of a driven member which may be in the form of a disk or wheel with means for applying to its periphery or to any other suitable part a series of blocks or like devices whereby contact may be established and broken in the sending circuit in a manner to send out signals similarly to the sending of signals by the ordinary key. The automatic transmitter of signals is provided with a suitable outfit of interchangeable blocks properly marked and readily applied or removed, each block containing a word or legend showing the information it is capable of sending, and the automatic side of the sending apparatus is appropriately extensive for the inclusion of as much information as is necessary.

The apparatus also includes a suitable motor which may be indicative of any driving power by which the block carrying part of the sending apparatus is given a motion

causing the sending out of signals in the desired order with repetitions of the signals as long as may be necessary.

The invention will be best understood from a consideration of the following detailed description, taken in connection with the accompanying drawings forming a part of this specification, with the further understanding that while the drawings show a practical form of the invention the latter is not confined to any strict conformity with the showing of the drawings, but may be changed and modified so long as such changes and modifications mark no material departure from the salient features of the invention.

In the drawings: Figure 1 is an elevation partly broken away showing a sending disk with some contact blocks thereon. Fig. 2 is an end elevation of the structure of Fig. 1. Fig. 3 is a diagram illustrating the sending station. Fig. 4 is a fragmentary perspective view of a portion of the sending wheel with some parts broken away. Fig. 5 is a section on the line 5—5 of Fig. 1 but drawn on a larger scale. Fig. 6 is a similar section of a somewhat modified form of the wheel. Figs. 7 and 8 are diagrammatic representations of different forms of current collecting means which may be employed.

Referring first to Fig. 3, there is shown a wheel or disk 1 mounted on a shaft 2, and this disk or wheel is assumed to be provided with a suitable number of contact blocks 3, as shown in Fig. 4, or contact blocks 4 as indicated in Fig. 6, the contact surfaces of either of the blocks 3 or 4 being the same; that is, they are made up of conducting surfaces 5 and electrically insulating portions 6. The blocks 3 or 4 may be made of metal and the wheel or disk 1 may be made of metal, in which case the blocks are always in electrical contact with the wheel, and the shaft 2 may be made of metal electrically connected with the disk 1. The insulating portions 6 are formed of any suitable material or composition customarily employed for the purpose, and may be in the form of sheets or strips as indicated, inset into the peripheral portions of the blocks 3 or 4. Since the disk 1 is circular, the blocks 3 and 4 conform to the curvature of the peripheral portion of the disk where they are carried in a manner to be described.

Arranged to engage the peripheral por-

tions of the blocks 3 or 4 is a collecting roller 7 which may be taken as indicative of any suitable current collecting device arranged to engage the exposed faces of the blocks 3 or 4. Referring once more particularly to Fig. 3 a conductor 8 is indicated as extending from and connected to the collector 7, and this conductor is connected to one side of a battery 9, or other suitable source of electric energy. The other side of the battery is connected to one end of a conductor 10, the other end of which is connected to one side of a relay 11, and this relay is connected by a conductor 12 to a brush 13 either bearing directly upon the shaft 2 or upon a collecting disk 14 best shown in Fig. 2.

The relay 11 is provided with an armature 15 movable between contacts 16 of platinum or silver in a circuit comprising a conductor 17, a battery 18, and one winding 19 of an induction coil 20. The other winding 21 of the induction coil 20 is connected on one side of a conductor 22 leading to an aerial 23. The other side of the coil 21 is connected to a conductor 24 leading to a ground 25 which may be the hull of the ship upon which the outfit is installed, or the device may be otherwise grounded. The relay circuit permits the use of a large induction coil and heavy charging current therefore without producing destructive sparking at the type or sending wheel. The conductors 22 and 24 have continuations terminating in a spark gap 26 as is customary, and are also bridged by a condenser 27, all as usual in wireless outfits.

The disk 1 is provided on its periphery with a channel 28 having marginal inturned flanges 29 on opposite sides. At some appropriate point in the continuity of the channel the flanges are omitted to provide an entering portion 30, whereby the blocks 3 or 4, as the case may be, may be introduced into and moved along the channel to appropriate points. At one end of the channel there is provided a stop member 31 which will represent the terminal point of travel of the blocks in one direction around the disk, while the blocks are being put into place.

In the form of block best shown in Figs. 4 and 5 each block is of appropriate length and curved in the direction of its length in conformity with the curvature of the channel 28 and has longitudinal grooves 32 on opposite faces to receive the flanges 29, so that the blocks once seated in the channel 28 cannot escape therefrom. The grooves 32 in the structure best shown in Figs. 4 and 5 are about midway of the height of the blocks 3, so that a portion of these blocks project radially outwardly beyond the outer edge of the disk 1, and attached to each block is a manipulating handle 33, whereby the block 65 is readily applied to and removed from the

disk. Of course, the handle 33 may be omitted but it is a convenient attachment to the block.

There is provided what may be termed an end block 34 which may be located at the end 70 of the series of blocks remote from the stop 31, and this end block is provided with a thumb screw 35 threaded through an appropriate portion of the block and provided with a clamp nut 36, so that the block may 75 be forced tight against the flanges 29 to hold the series of blocks from longitudinal movement. Space blocks 4^a with insulated surfaces are also provided and serve to separate words, numbers, etc. Insulation at the beginning of each block 3 and 4 serves to separate the letters where a block includes but a single letter or the like. The entering portion 30 of the periphery of the disk 1 is of sufficient length to receive the longest block 80 employed without interference from the flanges 29.

The collecting roller 7 is shown in Fig. 1 as mounted on one end of a rock arm 36, which arm is under the control of a spring 37, and in the particular showing of Figs. 1 and 2 the shaft 2 is journaled in bearings 38 surmounting standards 39 rising from a base 40. The arm 36 is pivoted between ears 41 on the base 40, and the spring 37 is interposed between the base 40 and the arm 36 thereby maintaining the roller 7 in constant engagement with the peripheral portions of the series of the blocks 3. Since the roller 7 must be insulated from the disk 1, the arm 36 may have a section of insulating material 42 interposed therein, and the conductor 8 is electrically connected to the roller 7 in any suitable way.

Instead of mounting the roller 7 upon one end of a rock arm it may be mounted on one end of a rod 43 carried by a post 44 and urged against the disk 1 by a spring 45 surrounding the rod 43. Instead of mounting the rod 43 upon a post 44 it may rise 105 from a block 46 made fast to the base 40 in underriding relation to the roller 1. The first described mounting for the roller is shown in Figs. 1 and 2 and the other forms are shown in Figs. 7 and 8, respectively. 110 These various illustrations of mounting of the roller indicate that such mounting may be quite widely varied without affecting the operation of the device.

In Fig. 6 the blocks 4 are of rectangular cross section, while the channel in the peripheral portion of the disk 1 may be deeper than in the structure of Figs. 1, 2, 4 and 5, this channel being shown at 28^a of Fig. 6, and is provided with inturned flanges 29^a 115 exterior to the blocks 4, so that the collecting roller 7 must enter between the flanges 29^a in order to make contact with the conducting portions of the blocks 4.

The disk 1 is rotated by any suitable 130

means, as, for instance, by means of a worm shaft 47 receiving power from any suitable source of which a spring motor may be taken as an example, although an electric motor 5 might be used for the same purpose. A spring motor, however, has the advantage of being always ready for operation. The shaft 47 carries a worm 48 engaging a worm wheel 49 on the shaft 2, thus imparting to 10 this shaft a slow rotative movement which may be continued indefinitely after the device is once started, and so long as the power stored in the motor is available.

It is assumed that the equipment diagrammatically represented in Fig. 3 is installed upon some vessel which does not come within the requirements of the law demanding a wireless outfit with skilled operators, and which types of vessels, therefore, have heretofore not provided wireless equipments 20 where the presence of one or two skilled operators is needful.

The equipment of the present invention is supposed to be under the control of the 25 captain of the vessel or some other responsible person, and in the event of accident suitable blocks 3 or 4 are chosen, the proper blocks being easily picked out from the blocks supplied with the equipment by the 30 words or legends thereon which are readily readable. If the accident be of such a nature as to place the vessel in imminent danger of loss, the person in charge selects blocks the first of which may be that corresponding 35 to the call "S. O. S." The next block may contain the telegraphic signal for the particular vessel. The next series of blocks are chosen to show the latitude and longitude of the vessel, and other blocks may be 40 chosen to indicate the condition of the vessel, such as "Sinking" or "Burning", or some other word of which the equipment may contain a suitable supply. Any other words may be added indicating the urgency of the 45 case. Having set up the series of blocks in the periphery of the wheel, the operator has but to start the motor, whereupon the wheel will begin and continue to turn at a suitable speed causing makes and breaks in the electric circuit corresponding to the telegraph 50 code and wireless signals will be caused and continue so long as may be needful, and all this without any attention whatever from the attendant.

55 The present invention provides a means whereby freighters, small steam ships, and all vessels carrying less than the number of passengers demanding the presence of wireless operators may be equipped at a moderate expense with a wireless outfit enabling the commander of the vessel to avail himself of the advantages of wireless telegraphy for summoning assistance in case of danger demanding such assistance, and this 60 without the necessity of any skilled assist-

ants, or any skill at all with respect to wireless telegraphy.

Besides a supply of blocks arranged to send out summons for help and the necessary information, the equipment may include other blocks containing information which experience may teach is of value. Of course, the present invention does not demand the employment of a receiving set, and if a record be kept of vessels equipped with sending sets only, other vessels provided with receiving sets will at once know the character of the vessel sending out the call for help.

The present invention does not include any improvements in the sending apparatus aside from the disk 1 and the parts directly associated therewith, and so in so far as the apparatus for producing ether waves is concerned any suitable arrangement may be employed.

What is claimed is:—

1. A wireless telegraphic transmitter, comprising a rotatable carrier and interchangeable contact members, the carrier having a peripheral channel for the reception of the contact members serially and at one end having permanent stop means for the contact members, and said contact members each having conducting and insulating portions together representing complete words, numbers, or the like, or recognized abbreviations thereof, and another member adapted to the peripheral channel and constituting a stop member for the end of the series of contact members remote from the permanent stop.

2. A wireless telegraph transmitter comprising a rotatable disk or carrier having a peripheral groove or channel, blocks interchangeably adapted to the channel and provided with conducting and insulating portions corresponding to chosen telegraphic symbols, and means for coupling up the rotatable carrier and blocks in the transmitter circuit, said disk or carrier having block retaining means at the peripheral channel portion, and said retaining means having its circumferential continuity broken to provide for the insertion into and removal of the blocks from the channel.

3. A wireless telegraph transmitter comprising a rotatable disk or carrier with a peripheral channel having inturned marginal flanges with the continuity of the flanges broken at a predetermined point to provide an entrance and exit opening for the channel, and blocks adapted to the channel to move lengthwise therein, said disk having a stop in the channel adjacent to the entrance opening, and one of the blocks being provided with retaining means for engaging the disk or carrier to hold the block in position to prevent escape of the other blocks.

4. A wireless telegraph transmitter comprising a rotatable disk having a peripheral channel, blocks adapted to the channel and provided with conducting and insulating surfaces, means on the carrier for preventing movement of the blocks circumferentially of the channel beyond a predetermined point, and one of the blocks having clamping means for holding it and the

5 blocks between it, and the means on the carrier for preventing movement of the blocks.

5. A wireless telegraph transmitter comprising a rotatable disk having a peripheral channel, blocks adapted to the channel and provided with conducting and insulating surfaces, means on the carrier for preventing movement of the blocks circumferen-

10

15

tially of the channel beyond a predetermined point, and one of the blocks having clamping means for holding it and the

20 blocks between it and the means on the carrier for preventing movement of the blocks, said clamping means on the last-named block including a set screw threaded through the block in position to engage the carrier, 25 and a lock nut on the set screw.

In testimony that I claim the foregoing as my own, I have hereto affixed my signature in the presence of two witnesses.

CHESTER MILLER AGNER.
